United States Patent Office.

CHARLES KORN, OF WURTSBOROUGH, NEW YORK.

Letters Patent No. 65,919, dated June 18, 1867.

IMPROVED MACHINE FOR DRESSING LEATHER.

The Schedule referred to in these Letters Patent and making part of the same.

TO ALL WHOM IT MAY CONCERN:

Be it known that I, CHARLES KORN, of Wurtsborough, Sullivan county, New York, have invented a new and improved Machine for Dressing Leather; and I do hereby declare that the following is a full, clear, and exact description thereof, which will enable others skilled in the art to make and use the same, reference being had to the accompanying drawings, forming part of this specification, in which—

Figure 1 represents a plan or top view of my improved machine for dressing leather.

Figure 2 is a side view of the same.

Figure 3 is an inverted detail plan view of the same.

Figure 4 is a detail side view, partly in section, of the same.

Similar letters of reference indicate corresponding parts.

This invention relates to certain improvements on a machine for dressing leather for which Letters Patent were granted to me on the twenty-fifth day of June, 1861.

The invention consists in the arrangement of a cleaner and sharpener, by which each knife, which is secured to an endless apron, is cleaned and sharpened after it has served to shave or "whiten" a skin of leather. The said sharpener and cleaner are combined in one sliding-block, and are made self-acting, and can be adjusted to knives of different sizes. When a knife has been cleaned and sharpened the sliding-block returns to position to operate the next knife, and so on, the whole device operating automatically, so that only the endless apron need be turned to set it all in operation.

A represents an endless apron, which is stretched around rollers B and C, that are hung in an inclined frame, D, as is clearly shown in the drawings, and substantially as described in the aforesaid Letters Patent. On the face of the apron are arranged any suitable number of knives E E, which are set obliquely across the face of the belt, as is clearly shown in fig. 1. F F' are two or more rods, which are firmly secured on the frame D above the apron A, and parallel with each other. They are both secured at each end in a block or bar, a, which slides on an upright bar, b, that is part of, or firmly attached to, the frame; and by a set-screw, c, they can be held in any position on the said bar b, and adjusted up and down, as may be desired. It will be seen that these rods are arranged obliquely across the apron A, and that they cross about at right angles to the direction of the knives E. On the rod F is arranged a block, G, which slides freely on the said rod. It has a guide or guides, d, by which it is steadied on the rod F'. The block G is arranged above that side of the apron on which the most advanced end of the knife is, as shown in fig. 1, the direction of the apron being indicated by an arrow in fig. 1. As the apron turns the most advanced end of the oblique knife comes against the block G, or would come in contact with the same if a slot or groove had not been provided in the block to receive the upper edge of the knife, (see fig. 3.) As the apron continues to move the front of the knife presses against the rear edge of the slot in the block, and forces the said block gradually towards the opposite end of the bars F F'. The front or cutting edge of the knife is pressed against a cleaner, e, which is fixed in the under side of the block G, and which is made of leather or other suitable material. f is an upright steel bar, which is pivoted to the block G by a pin, g, (see fig. 4,) and the lower end of which is pressed, by one or more springs h, against the front edge of the knife. This steel bar sharpens the cutting edge of the knife as the block G passes over the same. i is a steel plate, which is pivoted to the front of the block G, and which is pressed by a spring, j, to the knife. When the block moves, this plate i moves over the resharpened edge of the knife and smooths the same, preventing roughness or corrugations of the cutting edge. The plate f is slotted, and the plate i is secured, so that they both can easily yield to any fixed obstructions that may have accumulated on the knife, although the clearer will free the same to all probability as completely as possible. The bars f and i are both pivoted, not directly to the block G, but to a plate, k, which is slotted, and which is secured to the front of the block by means of screws l passing through the slots, so that, by means of this slotted plate, the bars f and i can be gradually lowered to accommodate the edge of the knife as the same is worn off, for which purpose the bars F F' are also arranged up and down adjustable. m is a spiral spring, fixed around the bar F' or F on that side towards which the block is moved on the bar F by the knife. This spring is compressed by the block when the same is thus moved by the oblique knife, and when the latter has passed the spring expands and throws the block back to its original position, a bolster, n, being secured to the bar F to receive the shock.

Having thus described my invention, what I claim as new, and desire to secure by Letters Patent, is—

1. The sharpeners *f* and *i*, when arranged on a sliding-block, *G*, either separate or in combination with the cleaner *e*, all made and operating substantially as herein shown and described.
2. The knife or knives *E*, when secured obliquely upon an endless apron, and when arranged in combination with the obliquely-set frame *F F'* and grooved block *G* in such a manner that the said block is moved by the knife, substantially as set forth.
3. The up-and-down adjustable frame *F F'*, in combination with the sliding-block *G* and knife or knives *E*, all made and operating substantially as herein shown and described.
4. The block *G* and knife or knives *E*, in combination with the spring *m* and frame *F F'*, all made and operating substantially as herein shown and described.
5. The knife or knives *E*, when arranged on an endless apron, *A*, in combination with the sliding-block *G*, and sharpeners *f* and *i*, and cleaner *e*, all made and operating substantially as herein shown and described.
